UNITED STATES PATENT OFFICE

ARTHUR I. RISSEK, OF CHICAGO, ILLINOIS, ASSIGNOR TO U. S. BOTTLEERS MACHINERY COMPANY, OF CHICAGO, ILLINOIS, A CORPORATION OF ILLINOIS

CAP FEEDER

Application filed April 10, 1929. Serial No. 354,014.

This invention relates to improvements in bottle capping machines, and more particularly to improvements in means for feeding the caps into a predetermined position, such as in cooperative relation with the bottles, or the capping mechanism of the machine.

In my invention, I provide means by which flat cylindrical caps can be fed, although other kinds of caps can be handled as well. 10 Flat screw caps, which are of thin, soft material, have been quite difficult to feed mechanically and place accurately in the chuck or carrying means for obvious reasons, and heretofore such caps have usually been placed 15 on the bottles manually. I also provide means for controlling the feeding of the caps directly by the bottles, so that a cap is not placed in position unless there is a bottle in the machine to receive the cap. I also provide 20 a feeder and mechanism which can be readily adjusted for different sizes of caps and bottles. Further objects and advantages of my invention will become apparent in the following description, with reference to the 25 accompanying drawings, in which:

Fig. 1 is a front view of a bottle capping machine showing an illustrative embodiment of my machine, with parts broken away and parts shown in section. The details and operation of the capping machine itself are more 30 fully described and claimed in my companion application for bottle capping machines.

Fig. 2 is a plan view taken substantially on the line 2—2 of Fig. 1.

Fig. 3 is a section substantially on the line 3—3 of Fig. 2.

Fig. 4 is a detail plan view of the feeding mechanism, taken substantially on the line 4—4 of Fig. 1.

Fig. 5 is a front elevation of the parts shown in Fig. 4.

Fig. 6 is a section on the line 6—6 of Fig. 4.

Fig. 7 is an elevation looking from the right side of Fig. 4, and shows the chuck C in an initial positional relation with the bottle cap B.

Fig. 8 is a section at 8—8 of Fig. 5.

Fig. 9 is an elevation of the left side of the feeder, taken on the line 9—9 of Fig. 5.

50 The bottle capping machine comprises a

short conveyor table 10 and a turret table 12, positioned behind the middle portion of said table. The conveyor table 10 is supported by pairs of legs 13, 14 and 15, and has a bottle conveyor belt 16 running across the top thereof. The belt 16 travels over the pulley 17, rotatably mounted in brackets 18 secured to the legs 13 at the left end of the conveyor table; and travels over the driving pulley 19 at the right end of the table. The driving pulley 19 is keyed on a shaft 20, journaled in the bearings 21, secured to the legs 15; and the shaft 20 is connected to the clutch shaft 22 by the chain belt 23.

The clutch shaft 22 is rotatably mounted in a frame plate 24, mounted on the front legs 13 and 14, and has, rotatably mounted thereon, a gear wheel 25 which is connected for rotation to the shaft by the clutch member 26, splined on the shaft 22, which is operated by 65 the clutch lever 27. Mounted on the rear, upwardly extending leg 13, is a motor 28 which is connected to the pulley shaft 29, journaled in the plate 24, by the belt 30, and a changeable speed connection from the shaft 29 to the gear 25 is made through the compound gear train 31, mounted on the plate 24. 70

The bottles D are carried across the conveyor table from the left to the right, and are diverted near the middle onto the turret table 12 by the curved end 32 of the guide rail 33, which is secured to the table 10 at the front edge of the conveyor belt 16. A guide rail 34 is provided at the side of the belt opposite to the rail 33, and a corresponding pair 80 of rails 35 and 36 on either side of the belt at the right end of the conveyor table, all of the rails being, of course, mounted on the table. The inner end 37 of the rail 35 is also curved over the belt to guide the bottles 85 back onto the belt as the bottles are returned from the turret table.

The turret table 12 is rotatably mounted in the turret frame, which comprises the posts 38 and 39, adjacent the rear side of the conveyor table, and the post 40, rearwardly spaced between the posts 38 and 39. Mounted on and connecting the posts, are triangular frame members 41, at the top, and 42 below the level of the conveyor belt. The shaft 43, 90

of the turret table 12, is rotatably mounted in the center hub 44, of the lower frame member 42, which hub also supports the turret table; and the upper end of the turret shaft 43 telescopes into the cam drum support shaft 45.1 which is slidably mounted in the upper frame member 41 and is supported by the shaft 43. Keyed to the shaft 43 and supported by the collar 45, fixed on the shaft 43, is a spindle carrying head 46 in which are mounted the spindle shafts 47, at regular intervals and equally spaced from the center of the head.

Near the middle, the spindle shafts 47 are provided with a fixed collar 48, and to the upper ends of the shafts are splined pinions 49, held between the bearing portions 50 and 51 formed in the head 46; and all of the pinions mesh with the center gear 52, which is held stationary on the shaft 45.1, while the head 46 rotates, thus revolving the spindle shafts as they are carried around on the head. The turret shaft 43, at its lower end, is provided with a bevel gear 53 fixed thereon, which meshes with a bevel pinion 54 keyed on the rear end of the clutch shaft 22, which end is supported in a bearing 55 bolted to the frame member 42.

The bottles, as they are deflected from the conveyor belt 16 by the curved rail portion 32, are shoved into semi-circular marginal pockets 56, formed in a ring 57 secured to the turret table 12 by a spring pressed lever 58, which is hinged to the inner end of the rail 54. The arrangement of the pockets 56 conforms to the arrangement of the spindles so that each bottle on the turret table is in vertical alignment with one of the spindles. For preventing the bottles from rotating at the rear of the turret to screw on the caps, I provide a belt 59. This belt 59 runs over the pulley 60, rotatably mounted in the frame member 61, which is fixedly supported on the rear post 40, the tightener pulley 62 adjustably and resiliently supported on said frame member, and the driving pulley 63. The driving pulley is keyed on a shaft 64, which is suitably connected for driving to the shaft 22, as shown in my companion application referred to above. At the right side of the turret, the bottles are deflected out of the pockets by the finger 65, secured to the rail portions 32 and 37, and the bottles then are guided back onto the conveyor belt in contact with the rail portion 37.

Threaded into the upper end of the shaft 45.1, is an adjusting screw 66 having a hand-wheel 67 secured to its upper end. On the stem 68 of the screw 66, is supported a yoke 69, in which the screw turns freely; and depending from the yoke, are the cam drum hanger rods 70. To the lower ends of the rods 70, is attached a spider 70.1, splined on the shaft 45.1, from which the cam drum 71 is supported by the bars 72. The cam drum

surrounds the spindle head 46 and has an irregularly shaped cam groove 73, in which the spindle controlling slide rollers 74 travel as the head 46 is rotated. The rollers 74 are attached to bars 75, which are slidably mounted in the head 46, and the lower ends of the bars are fastened to collars 76, which are slidably and rotatably mounted on the spindles 47. Suitable thrust bearings 77 and 78 are provided above and below the collars 76, and when the rollers are in the higher portions of the cam groove, the spindles are positively lifted with the bearing 77 in contact with the under side of the spindle collars 48. At the lower ends, the spindles are provided with flanges 79, fixed on the spindles; and coil springs 80 are interposed between the thrust bearings 78 and the flanges 79, so that the spindles may be resiliently depressed.

Rotatably secured to the lower end of each spindle and in frictional driving engagement with the lower face of the flange 79, is a capping head 81 in which is fixedly mounted the chuck ring 82. The ring 82 has a slightly tapered bore, which may have serrated walls, in which the bottle caps can be tightly engaged.

In the operation of the machine, the chucks are carried in an elevated position around the front of the turret where the bottles are being placed on and discharged from the turret table. As a bottle moves onto the turret table, a cap is inserted in the chuck, as will be described hereinafter. The chuck is lowered to place the cap on the bottle and screw it down. This latter part of the operation is accomplished while the bottle is held from turning by the belt 59, and next the chuck is withdrawn from the cap and raised to the starting height.

At the left side of the turret, vertically spaced plates 86 and 87 are secured to the bars 72, and in the plates are mounted two depending bars 88 and 89, on the lower ends of which is mounted the cap feed shelf 90. The shelf projects over the path of the bottles, and the chuck passes over and above the shelf. During this portion of the travel, the chuck is lowered over a cap placed on the shelf, as shown in Fig. 7, then lowered gradually to accurately position and press the cap up into the bore of the chuck ring, as the chuck is moving over the shelf and the extension plate 91, secured to the shelf, so that the cap is retained and picked up as the chuck is raised in leaving the shelf.

From the above, it will be perceived that it is necessary to position the cap on the table in close alignment with the chuck, and also that it is not desirable to have a cap inserted in the chuck unless there is a bottle in position to receive the cap from the chuck, because there is no other available means than the bottle provided for removing the cap from the chuck. It will also now be understood

that the capping mechanism may be adjusted for different heights of bottles merely by turning the screw 66, since the cam 46, which controls the heights of the chucks, and the shelf, fixed in cooperative relation with the chucks, are both supported by the adjusting screw 66.

The method and means of my invention for supplying and positioning the caps on the shelf will now be described.

On the left end of the shelf 90, just inside of the post 89, is secured a block 92, and opposite the block is a guide rail 93 adjustably secured to the shelf by means of the bolts 94, which are inserted through holes in the shelf and through slots 95 in the base portions 96' of the rail 93.

The caps are supplied to the channel C, formed between the members 92 and 93, from the magazine 96 which is mounted on the post 97 located at the left of the turret. To the lower end of the magazine 96, and forming a flexible continuation thereof, is a chute 98 consisting of the opposite arcuate side walls 99 and 100, to which are secured the bottom plate 101 and the top spaced plates 102. At the lower end of the chute, the lower edges of the side members 99 and 100, and the sides of the bottom plate 101, are cut away so that the sides rest on the top edges of the bar 92 and the guide 93, while the central lower end portion 103 of the plate 101 remains in close relation with the surface of the shelf 90.

For preventing the caps from jumping out of the channel C, and for providing ready access to the end cap at B₁, the lever 104 is hinged at one end to the bridge frame 105, which is secured to the shelf and spans the end of the channel C. The left or opposite end of the lever has a cross-pin 106 which engages the surfaces of the plate 102, so that the bar is slidably supported by the plates. It can now be seen that the shelf can be raised or lowered to different heights, together with the rest of the capping mechanism, without interfering with its relation to the magazine chute.

The movement of the caps from the magazine chute is controlled by the trigger plate 107, which is pivotally mounted on the stud 108', which is secured to the shelf 90. The inner end of the trigger is convex with a detent point 108 at the right side, which engages the cap at B₁ and holds it back in cooperation with the opposing rail 93, when the trigger is in normal position, as shown. When the trigger is moved clockwise, the cap at B₁ is released and the point 109, formed on the left side of the inner end of the trigger, swings in to intercept the succeeding cap and hold it until the trigger is restored to normal position, at which time the succeeding cap will be moved by gravity into the position B₁.

The trigger is stopped in counter-clockwise rotation by the pin 110, against which

the shoulder 111, formed on the trigger, strikes. The forwardly projecting end of the trigger has a slot 112 (see Fig. 2) in which the vertical rod 113 is slidably engaged. The rod 113 is carried by the spaced levers 114 which are secured on the shaft 115, and the shaft 115 is rotatably mounted in the bracket 116, which is mounted on the post 38. To the lower end of the rod 115, is secured a finger 117, which projects into the path of the bottles coming into position in the pockets on the turret table.

The shaft 115 is urged in clockwise rotation to hold the trigger in normal position with the shoulder 111 against the stop pin 110, by a coiled spring 118, which is extended between a pin 119, fixed in the shaft 115, and a pin 119', fixed in the bracket 116. Thus, it will be seen that as a bottle moves on the turret table towards the shelf 90, a cap will be released from the channel C by the bottle striking against the finger 117, and as the bottle passes out of engagement with the finger, the trigger will be returned to normal position by the spring 118 to hold the succeeding cap in the channel.

From the channel C, the released cap is carried out to the inner end of the shelf and positioned against the stop plate 120 by the constantly running carrier belt 121. The upper reach of the belt 121 slides on the surface of the shelf 90, and the belt is supported on pulleys 122 and 123, which are fixed on shafts 124 and 125, which are journaled in bearings 126 and 127, respectively, the bearings being mounted on the under side of the shelf.

The shaft 124 is extended toward the front of the machine and has a pulley 128 which is driven from the shaft 22 through a belt connection 129 to a shaft 130 journaled in the conveyor table frame and connected to the shaft 22 by the chain belt 131, as shown in Fig. 1. The belt 121 is tensioned by the pulley 132, which is mounted on the lever 133 and pivoted to the shelf, the pulley being pressed against the belt by means of the coiled spring 134.

The stop plate 120 is pivoted to the under side of the shelf 90 on a stud 135, fixed to the shelf, and the plate is urged in counter-clockwise rotation by the spring 136, which is coiled around the stud 135 and anchored thereto. The free end portion of the plate 120 is offset from the pivot and projects over the surface of the shelf, where it is provided with a notch 137 for locating the cap in alignment with the engaging chuck; and the plate is adjustably positioned by means of the lever 138. The lever 138 is pivoted to the upper surface of the shelf and has stepped notches 139 in which the pin 140, fixed to the plate 120, engages. The notches are so related to the pin 140 and the inner surface of the lever 138, that said surface cooperates

with the notch 137 in the stop plate 120 to form a pocket for the cap, and different sizes of pockets for different sizes of caps, but all in concentric relation, or on the same center.

5 By this means, an instant adjustment can be made for larger or smaller sizes of caps without changing the positional relation of the cap to the axis of the chuck. The shelf plate 91 is positioned at the rear side of the belt 121, and a second shelf plate 141 is fixed to the shelf along the front edge of the belt. These shelf plates 91 and 141 are thinner than the belt, as shown in Fig. 8, to insure engagement of the belt with the cap for 10 moving the cap along into position against the stop plate.

To review the cap feeding operation, the magazine is filled with a row of caps which move down by gravity as the caps are released from the channel C, and assume the ready position B₁. As a bottle is pocketed on the turret table, it strikes the finger 117 and a cap for the bottle is released by the resultant movement of the trigger. This cap is positioned on the shelf as the bottle is moving under the shelf, during which movement the chuck is brought down and loosely engages the cap, as shown in Fig. 7. Then, as the chuck moves along over the surface of the shelf plate 91, the chuck is lowered, through the travel of the corresponding roller 74 in the cam groove 73, and pressed down onto the cap, through the action of the spring 80, which is interposed between the spindle shaft 25 flange 79 and the collar 76, which is positively connected to the roller 74. The spindle shaft is being rotated constantly and it can be perceived the cap is accurately aligned in the chuck as it rests on the table, which is, of course, at right angles or normal to the axis 40 of the chuck.

When the cap is tightly engaged in the chuck, the chuck is raised and lifts the cap off from the table. As the chuck and bottle move away from the shelf, the chuck is lowered to thread the cap onto the bottle, and then frictionally rotated by the pressure between the flange 79 and the capping head 81, to screw the cap down.

45 The capping mechanism is included in my application Serial Number 354,013 where it is more fully described and claimed.

Having thus described an illustrative embodiment of my invention, my claims are:

50 1. In a bottle capping machine, a bottle support, a support for the capping mechanism for screwing a cap on the bottle adjustably movable with respect to the bottle support, a separately mounted cap magazine, and a chute hinged to the magazine and supported on the capping mechanism support.

55 2. In a bottle capping machine, a bottle support, a support for the capping mechanism for screwing a cap on the bottle adjustably movable with respect to the bottle sup-

port, a cap feed shelf mounted on the mechanism, a separately mounted magazine, and a flexible connection from the magazine to the shelf.

3. In a bottle capping machine, a cap feed shelf, an adjustable stop plate mounted on the shelf and having a notch for regulating the position of a cap, means for moving a cap into relation with the plate, and a member in cooperative relation with the stop plate in the different adjusted positions for forming pockets for the cap with the same central position.

4. In a bottle capping machine, a shelf, a stop plate hinged to the shelf, and a lever hinged to the shelf and engaged with the plate for forming a pocket for the cap.

5. In a bottle capping machine, a shelf, a stop plate hinged to the shelf, and a lever hinged to the shelf in angular relation to the plate and in adjustable cooperative relation therewith to form pockets for the caps.

6. In a bottle capping machine, a shelf, a stop plate hinged to the shelf, a lever hinged to the shelf and having a series of notches for engaging with the plate to form pockets for the caps, and means for retaining the plate and lever in engagement.

Signed at Chicago, Illinois, this 8th day of April, 1929.

ARTHUR I. RISER.
